UNITED STATES PATENT OFFICE

VINCENT G. APPLE, OF DAYTON, OHIO

WASHING MACHINE

Application filed June 14, 1928. Serial No. 285,372.

My invention relates to that type of washing machine wherein a tub comprising or containing the washing means has supported thereabove a wringer adapted to press the surplus water from the clothes after they are washed in the tub, and as the water used in such a machine is usually very hot and contains a solution of soap which is injurious to the hands an object of my invention is to provide a means whereby the clothes after washing may be raised above the water level and partly drained before they are fed by the hands thru the wringer. Another object of my invention is to provide a means which not only serves to raise the clothes above the water level for wringing but also serves to assist the washing action when occupying its lowered position in the tub. Other objects will be apparent to those skilled in the art from a consideration of the following description when taken in conjunction with the drawings, wherein

Fig. 1 shows a top view of a washing machine tub embodying my combined washing and draining device.

Fig. 2 is a longitudinal vertical section taken on the line 2—2 of Fig. 1 showing my device in position for washing.

Fig. 3 is a longitudinal vertical section similar to Fig. 2 but with the device in position for draining.

Fig. 4 is another longitudinal vertical device similar to Fig. 2 but showing how the device may be removed and returned through the opening in the tub.

Fig. 5 is a detail view in perspective of the device when removed from its guides in the tub.

Fig. 6 is a fragmentary perspective view of the inside of the tub showing one of the guides.

Fig. 7 is a cross section taken at 7—7 of Fig. 2.

Similar numerals refer to similar parts thruout the several views.

Referring to the drawings a tub 10 carries a vertically extending guide 11 at each end. A plate 12 has downwardly turned ends 13 to supply rigidity thereto. Depressions 14 extend thru plate 12 and thruout the down-

wardly turned ends 13 to have free bearing on guides 11. U shaped openings 15 in the downwardly turned ends 13 rest on pins 16 in tub 10 to locate and give support to plate 12. Heavy wires 17 bent at the upper end to handle form extend alongside of guides 11 at each end of tub 10 and are securely fastened to ends 13 of plate 12. Cross wires 18 connect the sides of wire handles 17 near their upper ends and are adapted to seat in notches 20 and 21 of guides 11. Plates 22 are joined to the sides of plate 12 by hinges 23. Springs 24 acting on plates 22 thru hinges 23 keep said plates seated against tub 10. At or near the widest portion of tub 10 grooves 25 extend thruout the entire length thereof.

The entire surface of plate 12 and a portion of that of plates 22 is perforated, (see Fig. 5), to assist washing action and for drainage. Tub 10 is of that type which is adapted to be rocked back and forth upon a pivot as at 27 to provide washing action and the position of the device relative to the tub as shown in Fig. 1 and 2 is that occupied while washing action is taking place. In operation the tub 10 is rocked and the clothes are thereby passed back and forth over the plates 12 and 22. The perforations in the plates supply a certain amount of rubbing action to the clothes and water forced upward thru said perforations by the rocking action of the tub further assists in the cleaning process.

When a tubfull of clothes have been washed and it is desired to pass them thru the wringer the operator grasps the handles 17 and first presses them slightly toward each other to disengage the cross wires 18 from the notches 21 in guides 11 then lifts up on the handles until cross wires 18 are level with notches 20 in guides 11. During this lifting action plates 22 have slid up the sides of tub 10 until they occupy that position shown in Fig. 3 wherein cross wires 18 rest in notches 20 of guides 11 and plates 22 rest their edges in grooves 25 of the tub. The position of the plates in Fig. 3 is so located as to be just above the water level in the tub and after allowing the clothes to drain thru the perforations in the plates they are passed thru a wringer (not shown).

If now another tubfull of clothes is to be washed in the same water the plates may be returned to the position shown in Fig. 2 by pressing inwardly on handles 17 to dis- 5 engage cross wires 18 from notches 20 and then pressing downward on handles 17 to seat the plates in the bottom of the tub as in Fig. 2. If however, the tub is to be cleaned and it is desired to remove the plates there- 10 from they may be lifted upwardly from the position shown in Fig. 3 and at a short distance above this position plates 22 will be turned downward by springs 24 so that the entire device may be taken thru the tub opening as shown in Fig. 4. After the tub and 15 the device has been cleaned the plates 22 are folded upward against the action of springs 24 until they are in a position as shown in the broken lines 22', Fig. 4 when the entire 20 device may be passed downwardly over guides 11 into washing position.

While I have herein shown and described an embodiment of my invention applicable to a tub of the oscillating type wherein the 25 device is necessarily foldable to allow its entry thru the relatively small opening there- 30 of, I consider as coming within the scope of my invention any similar device associated with washing machines of this or other char- 35 acter that raises and holds and drains the clothes so that they may be more comfortably handled to pass them thru a wringer and while my device as shown has several func- 40 tions, namely; to wash, to drain and to fold 45 to be removed, which are described as being used in combination, any two of said func- 50 tions are of considerable value when used one with the other. To further define what 55 I consider to be the scope of my invention, I 60 claim:

1. In a washing machine, the combination 65 of a tub, a perforated plate horizontally po- 70 sitioned in said tub, vertical guides in said tub, corresponding guides in said plate 75 adapted to engage said first guides, there be- 80 ing vertically spaced notches in the guides of said tub, and means connected with said plate to engage the said notches to retain the 85 said plate in different positions one position 90 above the other in said tub.

2. In a washing machine, the combination 95 of a tub, a perforated plate horizontally po- 100 sitioned in said tub, vertical guides in said tub, corresponding guides in said plate slid- 105 ably engageable with said first guides, there 110 being vertically spaced notches in the guides of said tub, resilient handles connected with said plate to raise said plate vertically in said tub, and means on said handles operable 115 by release of said handles to engage said notches to retain said plate in different hori- 120 zontal positions.

3. Washing apparatus comprising a tub 125 of different horizontal cross sectional areas 130 throughout its height and provided interior-

ly with vertical guides, there being an open- 140 ing in the top of said tub of less dimensions than the largest horizontal cross section, a 145 perforated plate having guides thereon re- 150 movably engaging said first guides adapted 155 to enter said opening when said plate is in a 160 horizontal position, means on said first guides 165 to maintain the horizontal position of said 170 plate at different heights in said tub, and per- 175 forated plates hinged to the opposite sides 180 of the first said plate and swingable outward- 185 ly to extended positions against the sides of 190 said tub at its larger horizontal cross sections 195 after said plates are lowered through said 200 opening, and means to retain said last named 205 plates in said extended positions.

4. Apparatus as described in claim 3 in 210 which said hinged plates are provided with 215 springs to urge said plates outwardly.

5. Apparatus such as is described in claim 220 3 wherein the tub is provided with ledges 225 at the largest horizontal area to support the 230 outer edges of said hinged plates.

In testimony whereof I hereunto set my 240 hand.

VINCENT G. APPLE.
